UNITED STATES PATENT OFFICE.

STEPHEN H. WHITNEY, OF SAN FRANCISCO, CALIFORNIA, ASSIGNEE OF ONE-FOURTH
TO ALBERT A. EDDIE, OF SAN FRANCISCO, CALIFORNIA.

ORE SEPARATOR.

Application filed October 21, 1918. Serial No. 332,228.

To all whom it may concern:

Be it known that I, STEPHEN H. WHITNEY, a citizen of the United States, residing at San Francisco, in the county of San Francisco and State of California, have invented new and useful Improvements in Ore Separators, of which the following is a specification.

It is the principal aim and object of the present invention to provide a device of the above mentioned character that is especially designed to separate platinum, osmiradium and gold from the silicate quartz and magnetic and chrome sands with which the heavier metals are usually associated and in fact for separating various ore wherein the components have a different specific gravity, pressure means being employed and manually controlled for insuring of the raising of the light particles permitting of the heavy particles to fall into a separate container.

More particularly the present invention contemplates the provision of a device of the above mentioned character wherein a pressure cylinder is employed in which a regulated and predetermined quantity of water or air pressure may be maintained for acting on the lighter particles of ore which is deposited in the separating chamber for raising and forcing the lighter particles to a point remote from the device and at the same time permitting the heavier particles to be deposited in a container positioned beneath the supporting frame.

It is an additional object of the present invention to provide a device of the above mentioned character wherein a magnetic wheel is employed to act in conjunction with the separating cylinder so as to attract metallic particles as they are raised upwardly by the pressure, while acting in conjunction with the wheel is a scraping blade for removing these particles so that they may be substantially deposited in a separate container therefor.

As a further improvement this invention embraces the provision of a device of the above mentioned character wherein a motor is employed and actuating by the fluid pressure in the discharge pipe to impart movement to the wheel and for simultaneously actuate the feeding and agitating means.

It is a more specific object of this inven-

tion to provide a device of the above mentioned character wherein improved means is employed for conducting a pressure supply into the pressure tank in such a manner as to produce an equal pressure in the tank; to improve the construction of the cylinders which are designed of transparent material permitting of the operator to see the separating action; and to provide manual operable valve means for regulating the pressure in the pressure cylinder and in the weighing chamber.

Among the other aims and objects of this invention may be recited the provision of a device of the character described with a view to compactness, and in which the number of parts are few, the construction simple and the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made without departing from the principle of operation of the various parts.

The invention is clearly illustrated in the accompanying drawings, in which:—

Figure 1 is a vertical sectional view of the invention.

Figure 2 is a top plan view thereof.

Figure 3 is a transverse section taken on line 3—3 of Figure 1.

Figure 4 is a transverse section taken on line 4—4 of Figure 1.

Figure 5 is a transverse section taken on line 5—5 of Figure 1.

Figure 6 is an elevational detail of the inner cylinder or shell which forms the separating chamber.

Figure 7 is a vertical sectional detail of a modified form of feeding means.

Figure 8 is a top plan view thereof partly in section.

Figure 9 is a top plan view of the structure of Figure 8.

Similar characters of reference are employed in all of the above described views, to indicate corresponding parts.

Referring now, more particularly, to the accompanying drawings there is provided a support comprising a frame 1 supported by legs 2, the frame and the legs being formed of metal tubing, while supported within the frame is an outer shell 3 which 10 forms a pressure chamber 4 and this shell is desirably of an octagonal configuration and is formed of angle strips 5 in which are transparent panels 6 preferably of glass. A cover 7 is mounted on the top of the shell 1 and is supported by the frame, and is formed with a central opening 8 for a purpose that will presently appear, while the bottom 9 is of a frusto-conical configuration and is formed with a tubular extension 15 20 for a purpose that will presently appear. Disposed through the opening 8 in the cover 7 is a sectional inner shell generally designated 11 which forms a separating chamber and preferably consists of an upper metallic section 12 which is formed 25 at its upper edge with an exterior annular flange 13 and near its lower edge with another exterior annular flange 14, while telescoped about the lower portion is a lower 30 transparent section 15. The flange 14 is bolted or otherwise secured as at 16 to the upper surface of the cover so as to be supported thereby while the lower edge of the lower glass section 15 terminates in 35 spaced relation to the bottom of the pressure chamber.

Disposed over the projecting upper edge of the section 12 of the inner shell 11 is a hood or casing 17, the lower flanged edge 40 18 of which is bolted or otherwise secured to the annular flange 13 as at 19. Positioned concentrically within the separating chamber is a vertically arranged conducting tube 20, the upper flanged edge of which is 45 secured as at 21 to the inner edge of an ore feeding pipe 22 which extends through the casing, as indicated. A vertical shaft 23 is journaled through the inner end of the pipe 22, the lower portion of the shaft being 50 formed with a feed screw 24 which operates in the tube and has suspended as at 25 from the lower end an inverted conical agitator or deflector 26, preferably of reticulated structure. By this particular construction when 55 the screw is rotated the mass of ore which passes through the pipe 22 is fed downwardly by the screw 24 and deposited on the deflector or agitator 26 so as to be subject to the pressure within the weighing chamber and will hereinafter become apparent.

In order to maintain an equal pressure in the pressure chamber or tank 4, a pressure supply pipe 27 is led to one side of the 60 top and is bent into an annular configura-

tion, as indicated by the numeral 28 and is provided with a series of perforations 29 through which the air or water passes. A manually operable valve 30 controls the passage of the water or air through this 70 pipe. Leading from one side of the hood or casing 17 is an outlet or discharge pipe 31, one section 32 of which has a manually operable valve 33 interposed therein for regulating the flow. A pressure gage 34 is 75 mounted on the cover to indicate the pressure of air or liquid within the tank or chamber 4. In operation the valves 30 and 33 being set as desired air or water is directed through the perforations 29 in the 80 nozzle so as to produce an equal distribution in the tank 4. In this tank air or water is forced upwardly through the weighing chamber to act upon the ore which is fed into the chamber by the screw 24, the deflector acting to scatter the ore so that the lighter particles will be carried upwardly under pressure and forced through the pipe 31, while the heavier particles will be deposited into a receiving container 35 85 detachably secured to the tubular extension 90 10 of the apparatus. The receiving container 35 is of the peculiar shape shown and on the interior is provided with a diagonally disposed or inclined plate 35^a which serves to divide 95 the container into two compartments, communication between which is effected through an opening 35^b made by forming the plate short at its lower end. Attached to the container and communicating with 100 the lower compartment there is a discharge tube 37 directed upwardly in a diagonal plane. On the diametrically opposite side of the container and also connected with the lower compartment there is a pipe 36 105 provided with a control valve 38 by means of which water under pressure is admitted to the lower compartment to discharge the deposits therein through the pipe 37. The 110 deposits from the apparatus are admitted through the tubular extension to the upper compartment and gravitate along the plate or partition 35^a then drop through the opening 35^b into the lower compartment from 115 which they are discharged through the pipe 37 by means of the fluid under pressure admitted to the lower compartment. At its lower extremity the container 35 is provided with a drain cock 38^a and the pipe 36 is similarly provided, being equipped with 120 a drain cock 38^b.

In order to remove metallic particles from the ore a magnetic wheel 39 is journaled on the shaft 40 and is positioned within the enlargement in the hood or casing 17 and also at a point near the discharge pipe 31 so that the wheel will attract the metallic particles and as the wheel rotates they will be removed therefrom by means of the 125 scraping blade 41 which is carried by the 130

- hood and is positioned in close relation with the periphery of the wheel. The metallic particles, of course, may be deposited in a suitable container, not shown. In order 5 that the wheel may be rotated simultaneously with the actuation of the screw 24 a beveled gear 42 is mounted on the shaft 40 and meshes with another beveled gear 43 carried by the upper end of the shaft 23.
- 10 As intimated, improved means have been provided for utilizing the air or water under pressure as it passes through the discharge pipe for actuating the magnetic wheel and screw. In reducing this feature 15 of the invention to practice a motor generally indicated by the numeral 44 is employed and consists of a casing 45 which is formed with one section of the piping 31, while rotatively mounted within the casing 20 is a rotor 46, the blades 47 of which are impacted by the water or air passing through the discharge pipe to rotate the rotor. A pulley wheel 48 is carried by the shaft 49 of the rotor, while operating over this pulley wheel is a belt 50 which is also trained about another pulley wheel 51 mounted on a projecting end of the shaft 40 and by this arrangement it is apparent that rotary motion 25 will be transmitted from the rotor shaft 30 to the shaft 40 by the transmitting belt to consequently assure of the magnetic wheel and feed screw operating simultaneously with each other.
- In connection with the foregoing it is to 35 be observed that the construction illustrated particularly designed for use when water under pressure is employed for separating purposes. However, the device is also designed to be used when air is used under 40 pressure and when dry substances are being separated. In accomplishing the latter purpose it has been found necessary to employ additional means for assuring of the maintenance of an equal pressure within the 45 tank. In the present instance instead of arranging the feed pipe 22 in the manner illustrated, a feed pipe 52 is connected to the hopper extension 53 of a hood 54, the base flange 55 of which is secured to the 50 base flange 21 of the inner shell and which surrounds the feed screw. This construction prevents the escape of air as the material in the hopper extension serves as a suitable plug and assures of the air passing 55 through the outlet or discharge pipe, the construction being illustrated in Figures 8 and 9 of the drawings.
- The mode of operation of the present invention may be reviewed as follows:—
- 60 Assuming that the parts have been assembled in the manner described and as indicated in figure 1, the valves 30 and 33 are adjusted to regulate the pressure of water or air through the nozzle 29 which 65 latter assures of the maintenance of an equal pressure within the tank 4. The air or water passes up through the separating chamber provided by the inner shell and acts upon the lighter particles so as to lift them upwardly and force them through 70 the discharge pipe under pressure. The pressure is utilized to actuate the motor by reason of the motion transmitting belt 50. It is apparent that rotary motion is imparted to the wheel which attracts the metallic substances, and also to the feed screw 75 so that these parts will operate simultaneously, the feed screw serving to force the mass of ore into the separating chamber and this ore is deflected or scraped by the 80 deflector or agitator which is suspended from the lower end of the screw when positioned within the separating chamber. The valves are supposed to be adjusted so that the heavier substances such as gold and 85 platinum which have a higher specific gravity will fall down and be deposited in the receptacle 35 and thence discharged therefrom in the manner hereinbefore described. The scraping blade 41 acts to remove metallic particles from gold and platinum ore, while the pressure gauge indicates the pressure of the ore or liquid in the 90 tank.
- What is claimed is:—
1. A device of the character described including a support, a pressure support mounted in the tank, a pressure supply pipe leading to the tank, a cylinder disposed concentrically within the tank and providing a 100 separating chamber, a conducting tube disposed concentrically within the chamber, a rotatably mounted feeding screw disposed through the tube, a conical deflector loosely suspended from the lower end of the screw 105 and positioned within the chamber, an outlet conducting pipe leading from the separating chamber, means mounted at the top of the chamber near the outlet for removing metallic particles from the ore, and means 110 at the bottom of the tank for receiving heavy particles.
2. A device of the character described including a support, a pressure tank mounted therein, a cover therefor and a central opening therein, a cylinder disposed through the opening in the cover and having the lower edge terminating short of the bottom of the tank providing a separating chamber, a hood for the cylinder, a tube disposed concentrically within the chamber, a rotatably mounted feed screw disposed in the tube, a deflector loosely suspended from the lower 115 end of the feed screw and positioned within the chamber, an inlet supply pipe leading to the tank, a nozzle at the inner end of the pipe arranged in surrounding relation with the separating chamber, means for regulating the admission of pressure to the tank, an outlet conducting pipe leading from the 120 tank, a valve at the inner end of the outlet pipe arranged to regulate the pressure of the 125 water or air passing through the outlet pipe, and a valve at the outer end of the outlet pipe arranged to regulate the pressure of the water or air passing through the outlet pipe.

chamber and through which light particles pass, receiving means at the bottom of the tank for accommodating heavy particles, means in the hood near the outlet conducting pipe for separating metallic particles from the ore, and means for regulating the exhausting of pressure from the tank.

3. An apparatus for the purpose indicated comprising a pressure tank, a cylinder disposed within the same and constituting a separating chamber, a conducting tube disposed within said weighing chamber and provided with inlet means at its upper end, a feed screw rotatably mounted in the conducting tube to feed the ore entering the latter downwardly into the separating chamber, means for admitting fluid under pressure to the tank and to the separating chamber to force the ore received thereinto upwardly through the latter, the separating chamber having a discharge means at its upper end, and means at the bottom of the tank for receiving heavy particles.

4. An apparatus for the purpose indicated comprising a pressure tank, a cylinder mounted in the pressure tank and constituting a separating chamber, a conducting tube disposed within the weighing chamber, a screw rotatably mounted in the conducting tube and having a conical deflector at its lower extremity, ore inlet and outlet means respectively for the conducting tube and the separating chamber, and means carried at the bottom of the tank to receive heavy particles.

5. An apparatus for the purpose indicated comprising a tank provided with a separating chamber and ore feeding means for the separating chamber, fluid pressure supply means connected with the tank to exert an upward pressure in the separating chamber, inlet and outlet means respectively for the conducting tube and the separating chamber, the tank having a conical bottom whose walls are disposed in downwardly converging relation and terminate at the lower extremity in a tubular extension, a receiving container detachably secured to said tubular extension, and fluid pressure means connected with said receiving con-

tainer to drive heavy particles therefrom to a point of collection.

6. An apparatus for the purpose indicated comprising a tank provided with a separating chamber and ore feeding means for the separating chamber, fluid pressure supply means connected with the tank to exert an upward pressure in the separating chamber, inlet and outlet means respectively for the conducting tube and the separating chamber, the tank having a conical bottom whose walls are disposed in downwardly converging relation and terminate at the lower extremity in a tubular extension, a receiving container detachably secured to said tubular extension and interiorly divided by an inclined plate defining two compartments communication between which is effected through an opening at the lower edge of said plate whereby deposits in the container gravitate through the opening of said plate to reach the lower compartment, a fluid pressure supply means communicating with the lower compartment of the container adjacent the opening in said plate and a discharge means for said compartment disposed at a diametrically opposite point from the pressure supply means.

7. An apparatus for the purpose indicated comprising a tank having ore inlet and discharge means and means for separating the lighter particles from the contained ore, the tank having a conical bottom whose walls are disposed in downwardly convergent relation, a receiving container detachably secured to the apex of said conical bottom and interiorly divided by an inclined plate defining two compartments between which communication is effected through an opening at the lower edge of the plate whereby deposits in the container gravitate through the opening of said plate to reach the lower compartment, a fluid pressure supply means communicating with the lower part of the container adjacent the opening in said plate and discharge means for said compartment disposed at a diametrically opposite point from the pressure supply means.

In testimony whereof I affix my signature.
STEPHEN H. WHITNEY.
